UNITED STATES PATENT OFFICE.

EMERY BÁRSONY, OF CASTLETON-ON-HUDSON, NEW YORK.

ELEVATOR SAFETY DEVICE.

1,133,084.

Specification of Letters Patent. Patented Mar. 23, 1915.

Application filed April 3, 1914. Serial No. 829,218.

To all whom it may concern:

Be it known that I, EMERY BÁRSONY, a subject of the King of Hungary, residing at Castleton-on-Hudson, in the county of Rensselaer and State of New York, have invented certain new and useful Improvements in Elevator Safety Devices, of which the following is a specification.

This invention relates to certain new and useful improvements in elevator safety devices.

Accidents having frequently occurred by reason of persons falling down an open elevator shaft, it is now designed to prevent all of such accidents by providing safety devices for elevators, whereby it is impossible to open the door of the elevator shaft at all times excepting when an elevator car is stationed at such door, while the power means of the elevator is automatically disconnected at all times when the shaft door is positioned open, which prevents any movement of the car at such times, and thereby doubly insuring against the exigency of an open unobstructed elevator shaft.

An object of the invention is to provide the said safety devices adaptable for the double door type of elevators and regardless of the form of motive power employed.

A further object is to provide a separate lock stop for each door of a double door elevator, automatically released at each floor landing with the service doors in operative alignment, while the motive power for the system is disconnected upon an opening of the car or inner door and is more completely removed from operation upon opening the shaft or outer door, while the inner door is locked against closing until after first closing the outer door and the closing of the outer door alone is insufficient to effect the complete operative connection, it being thus rendered impossible to operate the car until both the outer and the inner doors are closed.

With these general objects in view and others that will appear as the nature of the invention is better understood, the same consists in the novel combination and arrangement of parts hereinafter fully described, illustrated in the accompanying drawings, and pointed out in the appended claims.

In the drawings forming a part of this application and in which like designating characters refer to corresponding parts

throughout the several views:—Figure 1 is a vertical longitudinal sectional view taken through an elevator shaft with the elevator car shown therein partially broken away and positioned at a floor landing and illustrating the installation of the invention upon the double door type of elevator. Fig. 2 is a similar view of the empty shaft taken upon a plane perpendicular to the line of section of Fig. 1 and looking in the direction of the landing doors. Fig. 3 is an interior corner perspective view of a portion of the elevator shaft at a floor landing, showing the shaft door in its open position. Fig. 4 is a detail horizontal sectional view taken upon line IV—IV of Fig. 3 looking in the direction of the arrows, and showing the spring stop mechanism for the shaft door. Fig. 5 is a horizontal transverse sectional view upon substantially the same plane as Fig. 4, and showing the separate spring stops for the shaft and the car doors in their depressed inoperative positions as assumed when the car is positioned at a floor landing. Fig. 6 is a vertical sectional detailed view of the spring stop for the car door, shown in its operative locking position. Fig. 7 is a vertical sectional view taken upon line VII—VII of Fig. 5. Fig. 8 is a bottom plan view of a portion of the car showing the motive-power circuit switch open as positioned when both the shaft and car doors are open, the position of the shifting track-section being indicated. Fig. 9 is a similar view with the switch in its closed position as effected by closing both of the doors. Fig. 10 is a perspective view of the door portion of the car with the door in its open position, and parts being broken away. Fig. 11 is a perspective view of the motive-power circuit switch detached from the bottom of the car. Fig. 12 is a horizontal sectional view substantially upon the plane of the upper face of the shifting track section of Fig. 3. Fig. 13 is a detail vertical sectional view upon line XV—XV of Fig. 14. Fig. 14 is a view similar to Fig. 12 but with the parts shown as positioned with the shaft door closed. Fig. 15 is a perspective view of the shifting track section detached. Fig. 16 is a central horizontal sectional view taken through the shifting track section and the adjacent elements as shown in Fig. 12. Fig. 17 is a diagrammatic view of the elec-

tric wiring for the motive power circuit controller and switch as positioned upon the car all of the same being shown as positioned at a floor landing and Fig. 18 is a similar view showing the motive power switch and the controller in their closed positions and also showing the shaft door mechanism for partially closing the motive power circuit switch.

In taking up the detailed description of the entire device operative details of the double door system of safety devices will now be considered.

Referring more in detail to the drawings, the elevator shaft 30 is illustrated with the oppositely-arranged longitudinal guides 31 for the sliding reception of blocks 32 carried by the elevator car 33, which car in the form illustrated in Figs. 1 and 10 of the drawings, is provided with a sliding door 34 hereinafter termed the inner or car door. The elevator shaft is provided at each floor landing as 35 with a sliding door 36 herein referred to as the shaft doors.

With the car and shaft each provided with a separate sliding door illustrated as in Figs. 1, 2, 5, and 7 of the drawings, it is desired to automatically disconnect the motive power of the car at all times when the car is positioned at a floor landing when either one of the doors is in its open position and it is also desirable that both of the doors remain locked at all times excepting when the car is positioned at a landing. The car door 34 is shiftable to and from its closed position, being slidably-mounted in the groove 53 at the front of the car and when closed, the spring stop 44 is positioned rearwardly thereof and has a shifting outward and inward movement effected at each floor landing as hereinabove described. It will thus be seen that the stop 44 will be removed from the rearward path of travel of the car door whenever the shoe 46 is depressed upon reaching a floor landing, and at which time the car lamp circuit is completed for lighting the lamp, while the stop will rest rearwardly of the car door at all of the usual positions of the car when traveling between different floors, so that the car door remains locked by the spring stop 44 except when such stop is automatically released at each of the floor landings and only at which times the car door may be freely opened. A similar spring stop in the form of a pin 54 is provided for the shaft door 36 and adapted to engage the rear extension 55 of said door, which extension and door are slidably-mounted in the top groove 56 of a U-beam 57. This stop 54 when unlatched is adapted to be seated within the recess 58 of the shaft wall 59 and is mounted upon a longitudinally shiftable pin 60 normally projected outwardly by means of an encircling spring 61 bearing against the beam 57 within the

outer recess 62 thereof and against the head or shoe 63 of the pin 60, and whereby as illustrated in Fig. 13, the normal position of the stop 54 is rearwardly of the extension 55 and thus locking the door closed.

A stationary engaging block 64 is rigidly secured on the outside of the car and adapted to contact the shoe 63 of each floor landing as such landing is reached in the course of travel of the car up and down within the shaft and whereby upon the arrival of the car at any floor, the shoe 63 of that landing will be depressed by its engagement with the car-carried block 64 and the shaft door 36 of that landing will be automatically unlocked and allowed to be opened during such engagement between said shoe and block while upon the interruption of such engagement as caused by a movement of the car away from that floor, the stop 54 automatically re-locks the said shaft door 36.

In the present embodiment of the invention, the same has been illustrated in connection with the elevator system which employs electricity as its motive power for running the elevator car, although it is to be understood that the invention is equally adaptable, no matter what form of motive power is employed, such for instance as hydraulic or the counter-weight system and any of the same may be readily disconnected operatively and in an automatic manner by applying the present devices to the elevator system.

The electric line wires 65 and 66 desirably included in the cable 52 beneath the bottom of the elevator are provided with a manually-operated controller 67 and an automatic main switch 68 in circuit therewith. The line wire 65 is connected to the binding post 69 of the controller which controller is furnished with a contact arm 70 pivoted as at 71 while said pivot point is connected by the wire 72 with the post 73 of the switch 68. Contact points 74 of the controller are in constant circuit with the post 69 and consequently with the line wire 65 so that an electrical connection is made with the wire 72 whenever the arm 70 contacts either one of the points 74. The post 73 of the switch 68 is electrically connected with the pivoted switch blade 75 adapted to make an break contact with the slotted contact 76, which latter contact is in electrical circuit with the wire 66.

The switch 68 is secured to the car bottom 38 and the switch blade 75 has its outer end secured by an insulated link 77 to a connector 78, the opposite end of which is pivoted to an end of a pivoted lever 79, and also to the end of a leg 80 supplied with an outwardly projecting foot 81. The lever 79 being pivoted as at 82 to the car bottom has its free end connected to a spring 83 secured as at 84 to said bottom and whereby the switch blade 75 is normally held out of contact with

the contact point 76 and the switch maintained open with the motive power circuit broken.

The beam 57 is provided with a cut-away portion 85 at a point beneath the forward portion of the shaft door opening 86 and has positioned therein a shifting block 87 provided with a vertically-arranged U-shaped track section 88 having a curved cam flange 89 projecting from the shiftable block and normally projecting across the groove 56 and within the path of the door 36 upon its sliding movement and whereby the closing of the door engages the same against the flange 89 and forcibly moves the shiftable block with its track-section inwardly of the elevator shaft and in which projected position, it is retained by the door while the same remains closed, said door having a spring latch 90 for engaging a keeper 91 and only releasable without a key from the interior of the shaft.

When the car is positioned at a floor landing, the foot 81 is in alignment with the track section 88 and is slidably movable therethrough but normally held engaging the bottom thereof by means of said spring 83. By this arrangement, it will be evident that with the door 36 in its open position and the foot 81 positioned within the track section 88, a closing of the door 36 will move laterally inwardly the foot 81 as well as the switch blade 75 to the position illustrated in Fig. 8 but still out of engagement with the contact 76 and still maintaining the broken circuit. The car door 34 is adapted upon closing to engage the curved surface 92 of the block 93 mounted upon the leg 80, when such leg has been partially shifted by the track section 88 in the manner described and upon the closing of the shaft door 36. Such engagement of the car door 34 with such curved surface forces the leg 80 inwardly and away from the track section 88 to such a position as shown in Fig. 9 whereby the switch 68 is closed and is retained closed until the car door 34 releases the spring switch mechanism upon being again opened. It will be seen by this arrangement that when both doors are open, the leg 80 and its foot are projected in their outermost positions and with the switch 68 the farthest open and in such position an attempted closing of the door 34 brings the forward edge thereof in contact with the edge 94 of the block 93 and prevents a closing of said door 34 or a shifting of the foot 81, while as above set forth, upon first closing the shaft door 36 and thereby slightly shifting the foot 81 to the position shown in Fig. 8, it is possible to close the door 34, and in doing so, its engagement with the curved surface 92 of the block 93 completes the closing of the switch as shown in Fig. 9. These elements are those effectual in preventing the completion

of the motive power circuit until both of the doors have been closed and thus prevents any movement of the car when either one of the doors remains open.

The shiftable block 87 is resiliently maintained seated with its flange 89 projecting into the groove 56 by means of the spring members 97 engaging rearwardly extending pins 98 of said block. 70

From this detailed description it is believed that the complete operation of the device will be apparent. 75

In this double door system upon stopping the car at the desired floor, the spring stop means for whatever closures are employed are automatically released, allowing the opening thereof which is possible only when the car reaches a floor landing. 80

The complete automatic operation of the electric motive power switch 68 has already been fully described in connection with the double door type of elevator, and it is only necessary to further state that upon the arrival of the car at the desired floor landing, the doors are automatically released by the spring stop means and are manually slid to their open positions by the car operator and which is only possible from the interior of the car and shaft. The opening of the doors automatically opens the motive power switch, preventing any possible further travel of the car until such switch is closed, and which operation is automatically effected by closing both of the doors. 95

While the forms of the invention herein shown and described are what are believed to be preferable embodiments thereof, it is nevertheless to be understood that various forms and modifications may be had without departing from the spirit and scope of the invention as claimed. 100

What is claimed as new is:—

1. A device of the class described comprising an elevator shaft, a car vertically movable therein, a shaft door and a car door, a motive power switch upon said car and means for automatically releasing the said switch upon the opening of said doors. 110

2. A device of the class described, comprising an elevator shaft, a car vertically movable therein, a slidable shaft door, a slidable car door, a motive-power switch upon the car, automatic opening means for said switch operable upon an opening of the car door, said means obstructingly positionable within the closing path of movement of the car door when the shaft door is open. 115

3. A device of the class described, comprising an elevator shaft, a car vertically movable therein, a slidable shaft door, a slidable car door, a motive-power switch upon the car, automatic opening means for said switch operable upon an opening of the car door, said means obstructingly position- 125

able within the closing path of movement of the car door when the shaft door is open, means for shifting said switch and automatic opening means upon a closing of the 5 shaft door, and means for closing said switch upon the subsequent closing of the car door.

4. A device of the class described, comprising an elevator shaft, a car vertically 10 movable therein, a slidable shaft door, a slidable car door, a motive-power switch upon the car, automatic opening means for said switch operable upon an opening of the car door, said means obstructingly 15 positionable within the closing path of movement of the car door when the shaft door is open, means for shifting said switch and automatic opening means upon a closing of the shaft door, and means for closing said 20 switch upon the subsequent closing of the car door.

5. A device of the class described, comprising an elevator shaft, a car vertically 25 movable therein, a slidable shaft door, a slidable car door, a motive-power switch upon the car, and automatic opening means for said switch operable upon an opening of the car door, said means obstructingly 30 positionable within the closing path of movement of the car door when the shaft door is open.

6. A device of the class described, comprising an elevator shaft, a car vertically 35 movable therein, a slidable shaft door, a slidable car door, a motive-power switch upon the car, automatic opening means for said switch operable upon an opening of the car door, said means obstructingly 40 positionable within the closing path of movement of the car door when the shaft door is open, means for shifting said switch and automatic opening means upon a closing of the

shaft door, and means for closing said switch upon the subsequent closing of the 45 car door.

7. A device of the class described, comprising an elevator shaft, a car movable therein, slidable doors for said shaft and said car, a normally open power switch upon said car, and closing means for said switch 50 operable simultaneously with the closing of both doors.

8. A device of the class described, comprising an elevator car, a motive-power switch secured to said car and having a pivoted switch lever, an arm insulatively linked to said lever, a foot member pivoted to said arm and adapted for extending outwardly of the side of the car, a pivoted rod linked to said arm and foot member, and 60 resilient means secured to the free end of said rod and adapted for normally opening said switch.

9. A device of the class described, comprising an elevated car, a motive-power 65 switch secured to said car and having a pivoted switch lever, an arm insulatively linked to said lever, a foot member pivoted to said arm and adapted for extending outwardly of the side of the car, a pivoted rod linked to 70 said arm and foot member, resilient means secured to the free end of said rod and adapted for normally opening said switch, a slidable door for said car, and a cam block projecting from said foot member and extending in the path of movement of said door and adapted for closing said switch when the door is closed.

In testimony whereof I affix my signature in presence of two witnesses.

EMERY BÁRSÓNY.
